2,641,730

VELOCITY MODULATION AMPLIFIER TUBE

Emile Touraton, André Piquet, and Claude Dumousseau, Paris, France, assignors to International Standard Electric Corporation, New York, N. Y., a corporation of Delaware

Application October 7, 1947, Serial No. 778,361
In France August 21, 1946

Section 1, Public Law 690, August 8, 1946
Patent expires August 21, 1966

1 Claim. (Cl. 315—3)

1

The present invention relates to improvements in speed modulation amplifier tubes and, more particularly, to improvements in velocity modulation amplifier tube capable of wide frequency pass bands.

Velocity modulation tubes in which the resonant volumes are replaced by wave guides have been proposed. In these tubes, the output power is dependent on the length, and this presents certain drawbacks from the viewpoint of size.

One of the objects of the present invention relates to wide pass band speed modulation amplifier tubes that occupy small space.

Another object of the present invention relates to speed modulation amplifier tubes that furnish a considerable gain from low input levels.

According to one of the features of the present invention, a speed modulation amplifier tube comprises a vacuum envelope, a circular electron gun, a wave guide folded in spiral form, and a target electrode that collects the electrons emitted by the electron gun.

According to another feature of the present invention, the wave guide folded in spiral form is excited at one of its ends by the signal to be amplified, and the available energy is tapped at its other end. One or more openings are provided along the wave guide so as to permit passage of the electron beam with a suitable transit time. The spiral has such a pitch that the electrons take the same time to pass from one spire to another as the wave to be amplified does to pass over the same spire.

According to another feature of the present invention, a speed modulation amplifier tube comprises a wave guide folded in fretwork form and an electron gun that produces a narrow electron beam.

According to another feature of the present invention, a speed modulation amplifier tube comprises means that make it possible to produce an axial magnetic field in order to facilitate the concentration of the electron beam.

Other objects, features and advantages of the present invention will be found upon reading the following description given with reference to the appended drawings, which are without limitation and in which:

Fig. 1 shows diagrammatically an example of embodiment of a wide pass band velocity modulation amplifier tube incorporating features of the present invention.

Fig. 2 is a plan view of the wave guide of Fig. 1.

Fig. 3 is a fragmentary view showing section

through the wave guide of the example of embodiment of Fig. 1.

Fig. 4 shows sectional view of an example of embodiment of a circular electron gun.

Fig. 5 is a schematic of the developed image of the spires of the wave guide.

Fig. 6 shows an example of embodiment of the concentration of the electron beam by a magnetic field produced by a solenoid.

Fig. 7 shows another example of embodiment of a wide pass band speed modulation tube employing features of the present invention.

Referring to Figs. 1 and 2, these show an example of embodiment of a wide pass band speed modulation tube incorporating features of the present invention.

According to one of the features of the present invention, a speed modulation amplifier tube comprises a vacuum envelope 1 enclosing the various electrodes, particularly an electron gun 2, a wave guide folded in spiral form 3, and a target 4 which collects the electrons that issue from electron gun 2 after their passage through the spires of guide 3. The electrodes are supported in envelope 1 by supports 5 sealed to the walls of the envelope, or in any other known manner.

20 The outlet terminals of electron gun 2 and of target 4 are not shown in the drawings. The wave guide passes through the hermetically sealed vacuum envelope 1, and its ends are extended outwardly as shown in the drawing.

25 Fig. 3 shows a section of the wave guide of Fig. 1. The arrows indicate the path of the electron beam that passes over all or part of the guide's periphery. For this purpose, there is provided an electron gun of the annular type, e. g. like the one shown in Fig. 4. A ring-shaped cathode 6 is disposed within a focusing electrode 7, and it serves for forming an annular electron beam and guiding it to the outlet of cathode 6.

30 The electron beam that issues from electron gun 2 passes over all the spires of wave guide 3.

35 As shown by the arrows in Fig. 1, the amplifier is excited on the left hand side and the available energy is collected on the right-hand side at the outlet of the guide.

40 Taking two successive spires of wave guide 3, the tube operates like the amplifier described in the abovementioned patent application. It can accordingly be seen that the tube assembly may be likened to a certain number of elementary amplifiers in cascade, each of these elementary amplifiers consisting of two spires. In order that the energies of these elementary amplifiers may be additive and in phase, the pitch of the spiral of wave guide 3 has to be such that 45 the electrons take the same time in passing from

55

one spire to another as the wave to be amplified does in passing over the spire. The electron grouping thus takes place at each passage from one spire of the spiral to another.

The pass band of the amplifier made up in this way is theoretically infinite above the inherent cut-off frequency of the wave guide.

In order to make an approximate calculation of the gain due to the tube, examination is made of the developed image of the spires of the wave guide as shown in Fig. 5.

If E is the modulation voltage in the first spire S_1 , the developed voltage at an abscissa point X of the second spire will be KEX , and the developed voltage at the extreme right of the second spire will be KEL , L being the length of a spire. To this voltage is added the voltage E of the first spire, making a total:

$$E_2 = KEL + E = E(KL + 1)$$

If $KL > 1$, 1 may be neglected as regards KL , and $E_2 = KLE$.

At a point X of the third spire, the developed voltage will be

$$(KX \cdot E) \left(\frac{KX}{2} \right) = \frac{(KX)^2}{2} \cdot E$$

and at the extreme right of the third spire:

$$E_3 = \frac{(KL)^2}{2} \cdot E$$

If the total number of spires is n , the developed voltage at the extreme right of the nth spire will be:

$$E_n = \frac{(KL)^{n-1}}{(n-1)} \cdot E$$

Taking G to be the gain from the first to the second spire, the total gain will be:

$$G_n = \frac{G^{(n-1)}}{(n-1)}$$

This shows that the gain obtained may be considerable with a relatively small number of spires of the wave guide.

In order to prevent transverse dispersion of the electron sheet, means are provided for producing a uniform magnetic field parallel to the beam. It is possible, for example, to obtain this magnetic field by means of a solenoid having the same axis as the tube and traversed by a direct current of suitable value, as shown in Fig. 6.

An example of embodiment of a wide pass band speed modulation tube of medium power is shown in Fig. 7.

A vacuum envelope 12 encloses an electron gun comprising a cathode 13, e. g. of the circular type, and a focusing electrode 14 within which cathode 13 is located. A wave guide 15 is disposed along the tube and is folded in fretwork form, the wave to be amplified arriving on the left-hand side and the available energy being tapped on the right hand side, as shown by the arrows. A target 16 collects the electrons that issue from the electron gun after their passage through the horizontal portions of wave guide 15.

As explained above, the gain increases along the tube. There is no constant accompaniment by the electron beam, as described in the previous examples. Suitable phase conditions have to be respected in order to make additive the voltages developed in each elementary unit, and this determines the distance y between two consecutive horizontal portions.

The electron beam has however to be relatively narrow, and the available power is consequently limited.

As before, focusing means may be provided in order to guide the electron beam along the tube.

Although the present invention has been described for certain examples of embodiment, it is evident that it is by no means limited thereto, but that the same are capable of numerous variants and modifications without departing from the scope of the invention.

The described amplifier tubes have the advantage of small size owing to the special arrangement of their members, and they are capable of important gains from low input levels.

25 What is claimed is:

An amplifier of the velocity modulated type comprising a tubular envelope, an annular cathode within said envelope, an annular focussing electrode adjacent said cathode forming an electron gun therewith for producing an annular electron beam, a target electrode in the path of said electron beam, and a helical wave guide positioned between said electron gun and said target electrode, said wave guide helix having an inside diameter less than the diameter of said annular beam and an outside diameter greater than the diameter of said electron beam, said wave guide having a helical slot throughout its length, the diameter of the slot helix being substantially the diameter of said annular beam whereby said beam may pass through said slot throughout the length of said wave guide, said wave guide being open at both ends for the application of waves to be amplified at the end adjacent said cathode, and for the collection of the applied waves at the end adjacent said target electrode, said wave guide helix having a pitch such that electrons of said beam take substantially the same time passing from one turn to the next adjacent turn as said waves to be amplified in passing around a single turn.
